Philip L. Hall

Philip L. Hall, Esq. of the City of Baltimore and State of Maryland, Commissioner of the U.S. Patent Office, in the course of his duties for detecting fakes from drawings or for mechanical purposes, will be pleased to receive the present Hall Case. This is to witness that, C. J. Blodget, of the City of Baltimore and State of Maryland, has invented, or else has improved, an apparatus for detecting fakes from drawings, or for mechanical purposes, & that the following is a full and exact description of the apparatus, & the following is a full and exact description of the principles of the invention. It is to be understood that the following apparatus, & the principles of the invention, are part of the arrangement with an artist for tracing, drawing, or delineating through which upon the tracing or drawing, which are always present, is looked at fig. a. - To the front of this are attached the traces of c. which help assist the artist in the drafting of fig. b. The traces in which the artist c. are kept in their places as marked, as by means of the pinions or combs and some apparatus fig. 3. b. b is a rod passing from through the upper portion of the comb and lower part, or the upper spring would be between the tips of the traces and the upper right hand piece b. This spring being so that traces upwards and as the same move the jaws of the lower part, which are bent towards it in the front of c. This is sufficient to catch the traces c. To pass the traces with the hand to which the traces c. are attached, the end of the traces b. is so bent which contracts the spiral spring that the perpendicular arms of the traces and spread the jaws of fig. 3. b. from the traces c. and nearer and forward by the hand. The traces b. c. fig. 3. are shown in fig. 3. c. fig. 3. They are incorporated between c. c. fig. 3. (which are the traces no. 3. c. in fig. 132) and are designed for

two horses, one before the other. L.L. is for the hind horse &c. &c. for the leader. The jaws of the last into the wood or wooden L.L. the same as in the single horse apparatus on fig. 1. but the hind pieces L.L. from being detached before &c. are free. S.S. is a single tree (which is not drawn in proportion to as is not the shape) (s.p.) it being perpendicular to represent the principle. The principle of this invention is applicable to every kind of carriage or sleds, or to any kind of mechanical purpose where detaching apparatus are required. By the application of common hand levers instead of the single lever the downward pressure may be used, or by means of an upright proportioning rod and a hooked top a simple foot downward will effect the disengagement or, by means of a rod revolving down wards from any convenient part of the combined leaves the foot may effect the disengagement. I claim the principle of the plug &c. and the pieces L.L. together with the combined lever apparatus for detaching or disengaging horses or other animals from all kinds of carriages or sleds, for land road cars as well as mechanical purposes.
